(57) **CLAIM**

The ornamental design for a bracket applied to a window treatment as shown and described.

DESCRIPTION

FIG. 1 is a perspective view of a bracket applied to a window treatment showing our design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a perspective view thereof in an alternate position;
FIG. 10 is another perspective view thereof;
FIG. 11 is a front view thereof;
FIG. 12 is a rear view thereof;
FIG. 13 is a left side view thereof;
FIG. 14 is a right side view thereof;
FIG. 15 is a top view thereof; and,
FIG. 16 is a bottom view thereof.

The broken lines illustrate structure or features which form no part of the claimed design.

1 Claim, 8 Drawing Sheets

Related U.S. Application Data

continuation of application No. 29/772,085, filed on Feb. 26, 2021, now Pat. No. Des. 962,043.
